CLAIM

The ornamental design for a camera body, as shown and described.

DESCRIPTION

FIG. 1 is a top, front and side perspective view of a camera body showing our new design;

FIG. 2 is a front elevational view thereof;

FIG. 3 is a bottom plan view thereof;

FIG. 4 is a top, front and side perspective view thereof, with the bayonet lugs shown in a connectable position; and,

FIG. 5 is a perspective view thereof.

The parts shown in broken lines are only to illustrate the environment and are not claimed.
